UNITED STATES PATENT OFFICE.

ROBERT E. KIMBALL, OF CLEVELAND, OHIO.

TRANSFER-PRINTING MACHINE.

1,140,748.

Specification of Letters Patent. Patented May 25, 1915.

Application filed September 23, 1910. Serial No. 583,414.

To all whom it may concern:

Be it known that I, ROBERT E. KIMBALL, a citizen of the United States, residing at Cleveland, in the county of Cuyahoga and State of Ohio, have invented a certain new and useful Improvement in Transfer-Printing Machines, of which the following is a full, clear, and exact description.

This invention relates to transfer printing machines, particularly adapted for use on the so-called pay-as-you-enter or pay-within cars wherein the fare is paid and the transfer issued to a passenger when he boards the car.

The above types of cars and fare collection system while successful in many respects are not entirely satisfactory, due chiefly to the delays incident to the commonly employed system of issuing transfers in which the transferring line and time are punched by hand. This is particularly true during rush hours or when a number of passengers board or wish to board the car at the same time for the reason that the conductor as a rule is incapable of quickly calculating the time that the car is scheduled to arrive at a certain transfer point, and of adding to that time the proper stop-over period or the time allowed for the passenger to board the car at the intersecting line or the line to which transfer is to be made. Consequently, either the car is delayed an unnecessary length of time, or, as is frequently the case, the conductor will punch all the transfers for the time that his car is scheduled to reach the end of the line, with the result that passengers receiving transfers are allowed much longer stop-over privileges than that to which they are entitled.

The primary object of my invention is to provide a transfer printing machine by means of which transfers can be issued much more quickly and with less liability of errors than with the present system.

More particularly, the invention aims to do away with the necessity for all mental effort on the part of the conductor for placing on the transfer the proper time limit designation, and therefore in that manner to eliminate the chief cause of delay in issuing transfers at the present time.

The above objects are attained by my invention, which in one aspect comprises a transfer printing machine having a time printing member and a line selecting mecha-

nism which when actuated by the conductor, controls the time printing member or members so that the latter will be brought to proper position for printing the time or time limit in which the transfer is to be used for the particular line selected, this time limit being preferably a predetermined time period later than the time that the car is due to arrive at the transfer point. 65

Other features of novelty reside in the means whereby the machine can be readily used, both for the "out" and "in" or going and return trips, whereby the machine can be set or adjusted so as to print the proper 70 time limit for any transfer point, in case the car is running behind its schedule time.

The above and many other features of novelty will be specifically described in the specification and set forth in the appended 75 claims.

Reference is had to the accompanying sheets of drawings in which—

Figure 1 is a side elevation of the transfer printing machine with portions broken 80 away and certain portions on the interior of the casing shown in dotted lines; Fig. 2 is a vertical sectional view through the casing, showing the operating mechanism in front elevation; Fig. 3 is a horizontal sectional 85 plan view with certain portions of the mechanism removed and other portions broken away for the sake of clearness; Fig. 4 is a vertical sectional view substantially along the irregular line 4—4 of Fig. 6, looking in 90 the direction indicated by the arrow; Fig. 5 is a vertical sectional view substantially along the line 5—5 of Fig. 6, looking in the direction indicated by the arrow; Fig. 6 is a transverse sectional view substantially along 95 the line 6—6 of Fig. 1, looking in the direction indicated by the arrow; Fig. 7 is a side view of part of the operating mechanism, certain portions being in section, this view showing particularly the relation of the different parts; Figs. 8 and 9 are two views of part of the carrying mechanism between the minute type wheel and hour type wheel; Fig. 10 is a sectional view through the platen and a portion of the casing showing particularly the construction and arrangement of the strip feeding fingers; and Fig. 11 is a view of one of the transfers as printed by the machine. 105

The transfers are adapted to be printed 110 on a continuous strip 10, (see Figs. 3 and 4) which may be provided in the casing 11, in

the form of a roll 10^a. The strip is provided along opposite edges with notches 10^b which are adapted to be engaged by feeding fingers to be explained presently and which 5 divide or mark the strip into sections, each of which may have certain data previously printed thereon, as shown in Fig. 3, and each having spaces adapted to receive certain other data which is printed by the machine.

10 The strip is fed over the face of a platen 12 which is pivotally supported near its rear end upon a shaft 12^a extending between the side walls of the casing and is provided with a pair of rearwardly extending arms 12^b between which the strip is fed and by which the platen is pivotally mounted on the shaft, said arms having rearward extensions projecting beyond the shaft and provided with notches or recesses 12^c.

15 The platen co-operates with printing members mainly in the form of type wheels, to be referred to later, which are inked by an inking roller 13 supported by arms 14 secured to a shaft 15, extending between the side walls of the casing. One of the arms 14 has an extension 14^a which is adapted to be engaged by a roller-actuating pin 16 carried by one of two members 17 fixed to a shaft 17^a extending between the side walls 20 of the casing. A spring 15^a which surrounds the shaft 15 returns the inking roller to normal position,—the shaft being turned until a pin carried thereby engages a stop pin 15^b, (see Fig. 3). These members 17 25 are provided with upwardly extending lugs 17^b in which are pivoted strip feeding fingers 18 which are pulled yieldingly toward each other by a spring 19 and are adapted when moving forwardly to engage 30 in two of the oppositely disposed notches in the strip 10 after the printing operation, and thereby feed the strip forwardly an amount equal to the length of one section so that the end section thereof is projected between a 35 pair of knives or cutting blades 20 and 21, and is then severed from the strip. The shaft 17^a and the members which carry the feed fingers and also actuate the inking roller are adapted to be shifted by means of a link 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

is preferably mounted on trunnions 20^a which extend in sockets in the opposite side walls of the casing, and is pressed forwardly toward the movable blade 21 by a spring 20^b. The blade 21 is pivoted at one end so 70 that the strip will be severed first at one edge and then across to the other edge, as in the manner of shears having pivoted blades. This blade 21 is designed to be raised and lowered by mechanism including a bell crank 25 which is mounted on a pin 26 projecting laterally from one side of the casing and which is provided with a forwardly projecting arm 25^a having a ball and socket connection with the free end of 80 the blade 21 and having an arm 25^b which projects downwardly at substantially right angles to the arm 25^a and is connected by a link 27 to the lower end 28^a of a double arm 28 fixed to the shaft 12^a, previously referred 85 to. The arm 28 is secured to the shaft near one of the side walls of the casing, and near the opposite wall of the casing, the shaft 12^a has fixed thereto an arm 29 which is directly opposite the end 28^b of the double 90 arm 28. Extending between the portion 28^b of arm 28 and the arm 29 is a cross bar 28^c, and projecting outwardly from the portion 28^b of arm 28 is a pin 28^d which is adapted to be engaged by one of two slotted links 95 30 and 31 to actuate all the mechanism so far described, and other parts to be referred to presently, the pin engaging in the slots of said links and normally at the inner ends or bases of the slots. The slotted link 30, 100 it will be noted, is considerably shorter than the slotted link 31 and the former is connected at its upper end to a crank arm 30^a which is fixed to a main operating shaft A which extends through one of the side walls 105 of the casing and is provided at its outer end with a main operating lever A'. The longer slotted link 31 is connected at its upper end to a crank arm 31^a which is fixed to an auxiliary operating shaft B which, as 110 shown, is somewhat above and forward of the shaft A and has one end projecting through the side wall of the casing and provided with an auxiliary operating lever B'. In printing a transfer, as will be explained 115 more fully later, only one of the hand levers A' or B' will be turned,—ordinarily the hand lever A' being turned.

It may be here stated that when the arms 28 and 29 and bar 28^c are turned with the shaft 12^a by one of the actuating links last referred to, the bar 28^c engages first in the notch or recess 23^c on the arm 23^a of the bell crank 23 so as to shift said bell crank and the parts operatively connected therewith and then engages in the notches 12^c on the rearward extension of the platen 12 so as to shift the forward portion of the latter toward the printing members.

In connection with the pivoted platen, I

employ several printing or type carrying members, among which are four type wheels 33, 34, 35 and 36, which are mounted on a shaft 37 extending between the side walls of the casing and having one end projecting beyond one of the side walls and provided with a hand wheel 38, the type wheels 33, 35 and 36 being mounted loosely on the shaft 37, and the type wheel 34 being fixed thereto. The type wheel 33 is designed to print the different transferring lines or the lines to which transfer may be made from the car provided with the particular printing machine, and will be provided on its periphery in type form and at equal intervals the names of the different lines to which a transfer may be issued, and also the word "Emergency" or equivalent word or words, for a purpose to be explained presently; the type wheel 34 is designed to print the day of the month and will be provided with thirty-one equally spaced type numerals; the type wheel 35 is designed to print the hour in which the transfer is to be used and also the letter "A" or the letter "P" indicating whether the hour is before or after noon, and will be provided with twenty-four equally spaced hour type-numerals, with the letter "A" before twelve of them and the letter "P" before the other twelve; and the type wheel 36 is designed to print minutes or fraction of an hour in which the transfer is to be used and will be provided with twelve equally spaced minute type-numerals, in case the hour is divided into twelve parts for stop-over purposes. Ordinarily, these type wheels will be sufficient to print all the data necessary for issuing transfers, but in case the machine is to be used in a system or in a city where a charge is ordinarily made for a transfer, but under certain circumstances, or for certain lines free transfers are issued, I provide an additional printing member 39 which is provided with type for printing the word "Free" and which is carried by an arm 40 of a bell crank 40 provided with a second arm 40^b which is connected (see Fig. 5) by a link 41 to an arm or crank 42 fixed to the auxiliary operating shaft B. The shaft B, crank arm 31^a and slotted link 31 have the same function as the shaft A, crank arm 30^a and link 30, viz: the turning of the type wheels as will be explained presently, and the actuation of the inking roller, platen, the feeding fingers and the knife or cutting blade, but when the shaft B is turned by means of the auxiliary operating lever B', the printing member 39 bearing the legend "Free" will also be actuated or will be swung downward into co-operation with the platen, whereas when the operating lever A' is actuated, this printing member 39 will remain in retracted or inoperative position shown in Fig. 5. When the printing member 39 is shifted, it passes over

a stationary inking roller 51, whereby the type are inked.

The type wheel 33 which prints the different transfer line or lines to which transfers are issued is carried by a hub 55 of a gear 70 wheel 56, which is adapted to be engaged by a gear segment 57, which I term the "line wheel segment" and which is mounted upon a shaft 58 extending between the side walls of the casing. This segment has a hub 59 75 provided with an outwardly projecting arm or crank 60 (see Figs. 3 and 6) provided with a laterally projecting pin 61 which is connected by a spring 62 (see Fig. 3) to the cross bar 28^c previously referred to, this 80 spring serving, when the cross bar 28^c is turned or shifted, by either the link 30 or the link 31, to turn the segment, and consequently the line printing type wheel 33 a predetermined amount depending upon the 85 name of the particular line to be printed upon the transfer. The pin 61 is also connected to the cross bar 28^c by a slotted link 63, the cross bar 28^c engaging in the slot of the link. The purpose of this slotted link is 90 to return the segment 57 and the type wheel 33 to their normal positions after the transfer has been printed. The line selecting mechanism which when actuated determines the distance through which the segment 57 is 95 moved will be explained presently.

The type wheel 34 which prints the day of the month is normally stationary and will be adjusted in position each day by the conductor who will turn the shaft 37 and the 100 hand wheel 38 the proper amounts. Suitable indicating means on the exterior of the casing will be provided to enable the conductor to set the type wheel. As here shown, the indicating means consists of numerals 1 105 to 31, designated 38^a, on the hand wheel 38, and a pointer 38^b, on the adjacent wall of the casing.

The minute type wheel 36 is fixed to or carried by the hub 64 of a gear wheel 65 110 which engages or meshes with a gear wheel 66 of greater width than the gear wheel 65, said gear wheel 66 being secured to a rotary and endwise movable shaft 67 which extends between the side walls of the casing 115 and beyond one of the side walls where it is provided with a hand wheel 68. This gear wheel 66 is engaged also by a segment 69 mounted on the shaft 58, which also supports the segment 57, the segment 69, which 120 I term the "time wheel segment" being located next to one of the side walls of the casing. The segment 69 is provided with an inwardly projecting pin 70 which is connected to the cross bar 28^c by a spring 71 125 (see Fig. 3) similar to the spring 62, this spring 71 serving to turn the segment 69 as far as it is permitted to turn by the stop mechanism, to be referred to presently, when the cross bar 28^c is actuated by the link 30 or 130

the link 31. The segment 69 and the wheels connected thereto are adapted to be returned to normal position in the same manner that the segment 57 is returned to normal position, that is by means of a slotted link 72 which extends from the pin 70 and engages the cross bar 28°,—the cross bar of course engaging in the slot as is the case with the slotted link 63.

10 The carrying mechanism between the minute and the hour wheels 36 and 35 includes two disks 73 and 74, (see Figs. 2, 8 and 9) which are fixed to or move with the minute wheel 36, and a gear wheel 75 which at certain times coöperates therewith and which is mounted on a stud or shaft 76 projecting inwardly from one of the casing walls. By referring particularly to Figs. 8 and 9, it will be noted that the disk 73 is provided 20 with a notch corresponding to the slot between two gear teeth and that the disk 74 is provided with two teeth which project outwardly to the periphery of the disk 73. It will be noted also from these figures and 25 also from Fig. 2, that the gear wheel 75 has a portion provided with eight teeth, this portion projecting over the disk 74 and to one side thereof, and another portion provided with only four teeth,—this portion 30 projecting over the disk 73, the alternate teeth of gear 75 being shortened so as to provide at one part of the gear four teeth, and at the other part eight teeth. The portion of the gear having the eight teeth is engaged by a gear 77 mounted on a shaft 78 which extends across the casing, the gear 77 being provided with a hub carrying a gear 79 which meshes with a gear 80 which moves with the hour type wheel 35. Ordinarily, 40 or when two of the teeth of the gear 75 engage the smooth or unnotched portion of the gear 73, this gear wheel 73, and the gears connected thereto are held against rotation. However, once during each revolution of the 45 disk 73, and therefore of the disk 74, the notch 73a arrives opposite one of the teeth of the gear 75, and at the same time the teeth 74a come into driving engagement with the teeth of the gear 75, with the result that the 50 gear 75 will be turned by the teeth on the disk 74 through a space corresponding to two teeth. Consequently, through the medium of the gears 77, 79 and 80, at each revolution of the minute wheel 36, the hour wheel 55 35 will be turned a proper amount to advance said hour wheel one hour's space, or one twenty-fourth of a revolution.

It may be noted at this point that by moving the hand wheel 68 and shaft 67 inwardly 60 until the gear 66 is out of engagement with the teeth of the segment 69, and then by turning the hand wheel 68, the minute type wheel 36, and the hour type wheel 35 can be adjusted or turned to any desired position. 65 This is of importance for the reason that it

is necessary for the conductor to set the time wheel at the beginning of a trip so that the time wheels will print correctly for the first transfer point, and therefore for all subsequent transfer points providing the car is not delayed at any point along the line, and in case the car is delayed and is running behind its schedule time, the conductor can by means of this adjustment advance the time wheels so as to make the proper correction. 75 In order that the adjustment may be accurately made, I provide means for indicating the positions of the minute and hour type wheel, the indicating means for the minute wheel consisting in this case of numerals 5, 80 10, 15, etc., arranged on the hand wheel 68, (said numerals being indicated at 68a), and a stationary indicating pointer 68b adjacent said numerals. The means for indicating the position of the hour wheel includes a 85 shaft 82 which is supported in the side walls of the casing and has at one end which projects beyond the casing wall an indicating wheel 83 which is provided with hour numerals 83a and coöperates with a stationary 90 indicating pointer 83b. This shaft has fixed to it a gear 84 which meshes with the gear 79, which in turn meshes with the gear 80 fixed to the hour type wheel 35. The indicating wheels 68 and 83 turn at the same 95 rates as the minute and hour wheels respectively, and therefore if the numerals are arranged properly on said indicating wheels, the numerals opposite the pointers will be the same as the numerals on the type wheels 100 which are in printing position.

I shall now describe the preferred form of the line selecting mechanism, or the mechanism for causing the line wheel 33 to be brought to the proper position to 105 print the name of the desired line to which a transfer is to be made, and an important feature of my invention, viz: means whereby the actuation of the line selecting mechanism for any particular line 110 determines the extent of movement of the time wheels so that the proper time is printed on the transfer. While I have shown only the preferred form of line selecting mechanism, I wish it to be understood that 115 I do not desire to be limited to the same as this particular part of the machine may be varied somewhat without affecting its function as regards the controlling of the time wheels. The line selecting mechanism, as I 120 have shown it, includes a number of keys 85 which are arranged in a row and project upwardly through an inclined portion of the top of the casing, these keys having at their upper ends heads or buttons 85a on each of 125 which the name of a different transfer line or street may be printed, or any other means may be used for designating on the keys the names of the transfer lines. The keys are also provided with endwise or axial mov- 130

able shank portions 85^b each provided just below the top wall of the casing with lateral extensions or shoulders 85^c and 85^d which project in opposite directions, and at a distance below these shoulders, with a stop shoulder 85^e. Each of these keys or the shank portion of each key is provided with a member which, on being depressed, enters into the path of movement of the line wheel segment 57, and in this case these stop members are in the form of wires 86 which are connected to the extensions 85^c and extend downwardly and at their lower ends are provided with lateral extensions 86^a which are adapted to be moved in slots 87^a and 88^a of two plates 87 and 88 respectively, which plates extend downward from the top walls of the casing on opposite sides of the segment 57. The lower portion of the plate 88 is provided with a flange 88^b which guides the lower ends of the key shanks. The slots 87^a and 88^a in which the extensions 86^a of the wires 86 move are equally spaced and are of equal depth, the walls being arranged radially with respect to the axis of the shaft on which the segment 57 is mounted, and the lower ends of the slots being concentric with the axis of the shaft 58 and being arranged a short distance within or below the periphery of the segment 57. The keys are pressed outwardly by means of coil springs 89 which surround the lower portions of the shanks, but when a key is depressed a certain amount, it is adapted to be retained in its lowered position until another key is depressed, by means of a retaining or latching plate 90, (see Figs. 4 and 6), which is swung on trunnions 90^a and may be yieldingly pressed inward toward the key shanks by a coil spring 90^b surrounding one of the trunnions as shown in Fig. 4. This latching plate 90 is of sufficient length to extend along the entire series of keys and when a key is depressed, the plate will swing inwardly and engage a shoulder 85^e. This plate will retain the key in its lowered position until another key is depressed, when the latching plate will be swung outwardly so as to release a previously depressed key which is then returned to normal position by the corresponding spring 89, and said plate will immediately again swing inwardly so as to retain the last depressed key in lowered position. The latching plate 90 is caused to be swung outwardly so as to release the key which it had held in depressed position, by a portion of the shank of the key last being depressed, which portion projects outwardly beyond the shoulder 85^e, as shown clearly in Fig. 6, and causes the plate 90 to be moved off or out of engagement with the shoulder. Thus, it will be seen that the amount that the segment 57 and consequently that the line wheel 33 are rotated, and the name of the particular line which is

brought into printing position will depend upon the particular key which is depressed, and the wire 86 which is projected into the path of the segment.

In order that the line selecting mechanism may also control the time wheels, the movement of the keys of the line selecting mechanism, or at least of part of the keys is transferred to a stop device which controls the extent of movement of the segment which moves the time wheels,—this stop device co-operating with a number of notches or shoulders of a plate which moves with the time wheel segment, the distance between adjacent shoulders on the plate having a fixed relation to the distance and therefore the schedule time between adjacent transfer points, and the distance that the stop device is moved by depressing a certain key and the position of the particular shoulder which will be engaged by the stop device when the plate is rotated depending upon the distance of the particular transfer point or line corresponding to the key depressed from the end of the line from which the car started or from the first transfer point. This, it is believed, will be clear from the drawings taken in connection with the following description.

The notched plate which, as has been stated before, is movable with the time wheel segment and co-operates with the stop device has a series of notches or shoulders for the "Out" trip and a different series for the "In" trip, and therefore the plate must be changed before the conductor starts on either his "Out" or "In" trip. For convenience in changing the plate which is shown at 95, I prefer to arrange the same on the outside of the casing, the plate being movable about the end of the shaft 58 which projects slightly beyond the corresponding side of the casing and being caused to move with the time wheel segment 69 by means of a pair of pins which project outwardly from the segment 69 and extend through openings in the plate 95. These pins upon which the plate 95 are fastened consist of the pin 70, previously referred to, and a pin 96, which pins move through arc-shaped slots 97 in the side of the casing, said slots being shown by dotted lines in Fig. 1. Although separate plates may be employed for the "In" and "Out" trips, I prefer to use the same plate for both trips and to provide notches 95^a at one end of the plate for one trip and the notches 95^b at the opposite end of the plate for the other trip. It will therefore only be necessary for the conductor to reverse the position of the plate before starting a trip. This plate 95 is normally held in position on the pins and end of the shaft 58 by a clip 98 (see Figs. 1 and 6), which engages in a groove at the outer end of the shaft 58. By simply re-

moving this clip, the plate may be lifted off the pins 70 and 96, reversed in position, and again fastened in place by restoring the clip 98.

5 The stop member which co-operates with the notched plate 95 is shown at 99, and this member 99 is provided with a finger 99^a which extends outwardly through an elongated slot 100 in the side of the casing in the path of the shoulders 95^a when the plate is in one position, and the shoulders 95^b when the position of the plate is reversed. This plate is guided for movement along the inner side wall of the casing by a pair of 10 guiding members 101 and is supported upon two parallel rods 102 carried by the ends of two sets of parallel arms or levers 103, which arms are pivotally supported intermediate their ends on pins 104 carried by members 105 15 secured to the top of the casing and support on the ends opposite to the ends which carry the stop member 99, a notched plate 106 which is located beneath the shoulders 85^a on the shanks of the keys 85 of the line selecting mechanism. This plate is provided at its upper edge beneath said shoulders 85^a with notches forming a series of steps 106^a, (see particularly Fig. 5), so that when different keys are depressed, the plate 106 will 20 be depressed different amounts, and consequently the stop device 99 which moves parallel to the plate 106, will be raised different amounts so that the finger 99^a of the stop device will be projected in the path of different shoulders 95^a or 95^b.

25 By referring particularly to Fig. 5, it will be noted that the plate 106 does not, as here shown, extend beneath the shoulders 85^a of all the keys, and that when either of the first three keys are depressed, plate 106 will not be shifted, and therefore the stop device will not be shifted. This arrangement is provided for the reason that I prefer to employ what is known as an emergency key which may be the first or uppermost key and will be utilized for printing an emergency transfer without any line limitation thereon, such for example, as are commonly used when a previously issued 30 transfer becomes worthless, due to an unusual delay before the transfer point is reached, and for the further reason that I prefer that the time wheels be set prior to the start of a trip for the time that the car 35 is scheduled to arrive at the first transfer point. Of course, the time wheels could be set for the start of a trip, but in such case, a movement of the time wheel would be necessary to print the proper time for the first 40 transfer point, and a greater movement would be necessary for each subsequent transfer point.

45 When either the second or third keys are depressed when the car is, say, on the "Out" trip, so as to print a transfer for the first or

second intersecting lines which, in this case, would be located so near each other that the same time would be printed on a transfer to either of said lines, the line wheel segment would be moved so that the name of 70 the proper transfer line would be printed on the transfer, but the time wheel segment will not be shifted for the reason that the stop plate 106 and the stop device 99 will not be shifted. However, the proper time will be 75 printed on the transfer for either of these two transfer lines for the reason that, as before stated, before the car is started from the end of the line, the conductor will set the time wheels to positions such that without any further movement of the time wheels, the proper time will be printed on the transfer when the car reaches this transfer point. In other words, the time wheels will be set to positions such that when the 80 machine is operated to print the transfer, the time which will be printed on the transfer will be a certain period, say ten minutes, or the proper stop-over period later than the schedule time at which the car should 85 reach the transfer point. When, however, either the fourth or fifth key, or in fact any one of the other keys is depressed, the stepped plate 106 will be lowered a pre-determined amount so as to raise the stop 90 device 99, and therefore the stop finger 99^a an amount sufficient to bring the stop finger 99^a out of engagement with the first shoulder or the shoulder which it normally engages, as shown in Fig. 1, into the path of a 95 certain other shoulder. Therefore when the machine is operated to print a transfer for say the second transfer point, the line wheel segment will be moved a certain amount which is determined by the position of the 100 stop wire carried by the particular key depressed, and the time wheel segment will be turned a certain amount which will depend upon the distance of the second shoulder from the first shoulder, and this distance will be directly proportionate to the 105 schedule time between the first transfer point and the second transfer point. If this time is say twenty minutes, or approximately twenty minutes, the time which is 110 printed on the transfer for the second transfer point will be twenty minutes later than the time which is printed on the transfer for the first transfer point.

115 Since on the "In" or return trip the transfer points are passed in the reverse order to that when on the "Out" trip, the notches 95^b or those which are employed for the return trip will be the same in number, spacing and length as the notches 95^a, except that the former are just in the reverse order to the latter. Before the conductor starts on the return trip, the plate 95 will be reversed in position and the time wheels will be set for the time at which the car is 120

5 scheduled to reach the first transfer point which was the last transfer point when the car was on the "Out" or going trip. The machine is operated on the return trip in the same manner as on the going trip. The notches 95^a and 95^b on the plate 95 will be cut with great accuracy and the distance between the adjacent shoulders and the number of shoulders will, of course, vary with 10 the line on which the particular machine is being used and will depend upon the number of transfer points and the distances between them.

15 When the car is about to start on the "Out" trip, the conductor will by means of the hand wheel 68, set the time printing wheels so as to print the correct time for the first transfer line or lines, if there are 20 more than one transfer line, or transfer point reached at about the same time. When a passenger boards the car, pays his fare and requests a transfer to a certain line, the conductor will depress the key corresponding to that line so as to interpose in 25 the path of movement of the line wheel segment, the proper stop wire, and at the same time to cause the stop finger 99^a to be placed in the path of the proper shoulder of the plate which is fixed to the time wheel segment. The conductor will then pull downward 30 either the main operating lever A' or in case the machine is used in a system wherein distinction must be made between transfers which are granted without charge 35 and those for which a charge is made, and if a free transfer is to be issued, the auxiliary operating lever B'.

40 Assuming that the main operating lever A' is pulled downward, the short link 30 by its engagement with the pin 28^a will shift the shaft 12^a and the members 28 and 29. By means of the springs connecting the cross bar 28^c with the line wheel segment and the time wheel segment, these segments 45 will be moved until the respective stop members are engaged, after which further or continued movement of the cross bar 28^c simply stretches the two springs. Furthermore, at the beginning of the movement of 50 the double arm 28, the movable blade 21 is elevated and shortly after the cross bar 28^c engages in the notch 23^c of the bell crank 23, causing the inking roller 13 to be actuated so as to ink the type of the four 55 printing wheels, the line and time printing wheels having meanwhile been brought to proper position, and at the same time that the inking roller is actuated or moved past the type to be inked, the feeding fingers are 60 retracted. After the bell crank 23 has been moved a predetermined amount, the cross bar 28^c engages in the notches 12^c on the arms 12^b of the platen 12, causing the forward portion of said platen to be elevated 65 and carrying upward the end section of the

paper strip 10, and causing the proper data to be printed on such section.

70 When the platen is raised and the feeding fingers are retracted in the manner above stated, the upper ends of said fingers pass below the upper face of the platen and below the paper strip, and therefore to prevent this rearward movement of the fingers from causing a backward movement of the strip 10 and also to prevent the strip slipping backward when the platen is elevated, I employ short ratchet fingers 108 which are pivoted on the side portions of the platen just beyond the edges of the strip and are arranged in a manner such that the free 80 ends of said fingers will engage in a pair of the opposite notches provided at the edges of the strip.

85 After the transfer is printed in the manner above described, and after the operating handle is released by the conductor, a spring 109 connected to the bell crank 23 and a spring 110 connected to arm 28, return said parts and the members connected thereto to their normal positions. That is, the platen 90 is lowered and at the same time, the feed fingers move forwardly and the inking roller returns to the position shown in Figs. 5 and 7. The platen may be lowered until it reaches a stop 111, either by its own 95 weight or by gravity with the assistance of a spring 112. As the platen moves downwardly, and the feed fingers move forwardly, the upper ends of the fingers rise above the platen, the upper ends of the fingers being curved outwardly, as shown in Fig. 10, so that they may be extended above the platen, and then the fingers slide along the sides of the platen and along the edges 100 of the strip, and just as, or substantially just as the platen reaches its lowermost position, the fingers drop in the pair of notches in the strip next to or adjacent the forward pair of notches, the sides of the platen being recessed, as shown at 12^d (see Fig. 3) to permit the fingers under the action of the connecting spring 19 to engage in these notches, and then further forward movement of the fingers moves the strips forwardly through a discharge or outlet slot 11^a of the casing 11^b, (see Figs. 3 and 5), and between the blades an amount equal to the length of one section, after which the printed section is severed from the strip by the blades or cutters, and drops onto a suitable platform 120 11^b on the exterior of the casing. The transfer may then be picked up by the passenger or passed to him by the conductor.

115 While the parts just described are being returned to normal position and while the strip is fed forwardly and the end section is being severed, the segments 57 and 69 and the parts connected thereto including the time and line type wheels are also returned to 123 normal position by the cross bar 28^c and the 130

two slotted links 63 and 72, which are connected to the segments and are engaged by the bar 28^c during the return movement of the latter.

- 5 The object of employing the springs 62 and 71 between the bar 28^c and the segments, for moving the segments and therefore the printing wheels from normal position to printing positions, is that regardless of 10 the extent of movement of the segments and printing wheels and regardless of whether they are moved during the maximum arcs or are not moved at all during the printing of the transfers, the operating levers will 15 always be moved the same amount.

When the operating lever B' is actuated, the same movements take place and the same results are obtained as above described, but also the printing member 39 is swung downward so as to print the word "Free" on the transfer in addition to the matter printed by the type wheels, and then on the return of the parts, the printing member 39 is returned to normal position.

- 20 25 In case it is desired to print an emergency transfer for a particular line, the conductor will depress two keys of the line selecting mechanism, namely,—the emergency key, and the key corresponding to the line to 30 which the transfer is to be issued. By depressing the emergency key, the line wheel segment and consequently the line printing member will be held against movement when the operating lever is depressed. Consequently, the word "Emergency" will be 35 printed on the transfer in place of the name of a transfer line, the word "Emergency" being at the bottom of the line printing wheel or being in printing position when 40 the line printing wheel is in normal position. By depressing in addition to the emergency key, the key corresponding to the line to which transfer is made, the latter key controls the movement of the time 45 wheel, and therefore there will be printed on the transfer, time data which bears a fixed relation to the time that the car is scheduled to arrive at the transfer line.

If desired, some means such as a spring 50 113 (see Fig. 3) may be employed to prevent the strip 10 being lifted from the face of the platen. The spring, as here shown, is fastened to the arms 12^b of the platen and bears yieldingly on the strip.

55 Having thus described my invention, what I claim is:—

1. In a transfer printing machine, line and time printing members independently movable during the operation of the machine, a movable line selecting mechanism associated with the line printing member, and means whereby the movement of the line selecting mechanism controls the movement of the time printing member.
- 60 65 2. In a transfer printing machine, line and

time printing members independently movable during the operation of the machine, and means associated with both printing members whereby when a transfer is printed for any particular line the time printing member is caused to print a time which has a definite relation to the time that the car is scheduled to arrive at that transfer point.

3. In a transfer printing machine, line and time printing members relatively movable 75 during the operation of the machine for printing line and time data for a number of transfer lines, and means comprising a selecting mechanism for controlling the movements of the line and time printing 80 members so that when a transfer is printed for any particular line the time printing member is shifted an amount sufficient to cause the time which is printed on the transfer to be a predetermined amount later than 85 the time that the car is scheduled to arrive at the transfer point.

4. In a transfer printing machine, independently movable printing members for printing line and time designations, a line 90 selecting mechanism for controlling the movement of the line printing member, and means actuated by the line selecting mechanism for controlling the movement of the time printing member.

5. In a transfer printing machine, movable printing members for printing line and time designations, a line selecting mechanism for controlling the movement of the line printing member, a stop mechanism for controlling the movement of the time printing member, said stop mechanism being controlled by the line selecting mechanism.

6. In a transfer printing machine, movable printing members for printing line and time designations, a line selecting mechanism including a plurality of separately movable stop members for limiting the movement of the line printing member, and stop mechanism for the time printing member 105 controlled by the line selecting mechanism.

7. In a transfer printing machine, movable members for printing different line and time designations, means for shifting said members and for causing the printing of line 115 and time data, and means for controlling the movement of the time printing member comprising a member having definite stop points thereon, the relative spacing of said stop points having a fixed relation to the 120 distances between transfer points or stations along the line on which the machine is employed.

8. In a transfer printing machine, movable members for printing different line and time designations, and means for controlling the movement of the time printing member comprising a stop mechanism including a member having stop points thereon corresponding to different transfer 125 130

points, the spacing of said stop points being proportionate to the distances between the transfer points.

9. In a transfer printing machine, movable members for printing different line and time designations, and means for controlling the movement of the time printing member comprising a stop mechanism including a movable member having a number of stop shoulders, and means adapted to engage said shoulders, the spacing of said shoulders being proportionate to the distances between transfer points.

10. In a transfer printing machine, movable printing members for printing line and time designations, a stop mechanism for controlling the movement of the time printing member, said stop mechanism being controlled by the line selecting mechanism, and including a movable member having a number of stop shoulders, and means adapted to engage said shoulders, the spacing of said shoulders being proportionate to the distances between transfer points.

11. In a transfer printing machine, relatively movable printing members for printing different line and time designations, a line selecting mechanism for causing the line printing member to be brought to the proper position, a stop mechanism for the time printing member comprising a member having spaced shoulders, and means adapted to engage the shoulders, said means being actuated by the line selecting mechanism.

12. In a transfer printing machine, movable members for printing line and time designations, a line selecting mechanism for controlling the movement of the line printing member, mechanism for controlling the movement of the time printing member comprising movable means controlled or shifted by the line selecting mechanism, and a member which is connected to the time printing member, and has a plurality of stop shoulders adapted to be engaged by said means.

13. In a transfer printing machine, movable members for printing line and time designations, a line selecting mechanism for controlling the movement of the line printing member, mechanism for controlling the movement of the time printing member comprising movable means controlled or shifted by the line selecting mechanism, and a member which is connected to the time printing member and has a plurality of stop shoulders adapted to be engaged by said means, the spacing of said shoulders having a fixed relation to the distances between transfer points.

14. In a transfer printing machine, movable members for printing line and time designations, a line selecting mechanism for controlling the movement of the line printing member, a stop mechanism for the time

printing member controlled by the line selecting mechanism, said stop mechanism including a plate having a series of shoulders and a movable stop device which coöperates therewith, said plate being connected to the time printing member so that it will move therewith and being secured in position in a manner such that it can be removed.

15. In a transfer printing machine, a casing, a plurality of printing members for printing line and time designations, a line selecting mechanism for controlling the movement of the line printing member, stop mechanism for the time printing member, including a plate having a series of shoulders, the relative spacing of which has a fixed relation to the relative distances between transfer points along the line on which the machine is used, and a movable stop device which coöperates with said plate, a support for said plate movable with the time printing member, said plate being removably attached to the support on the exterior of the casing.

16. In a transfer printing machine, a plurality of movable printing members for printing line and time designations, a stop mechanism for controlling the movement of the line printing member, and a stop mechanism for controlling the movement of the time printing member, said last named stop mechanism including a plate having two series of shoulders, and a movable device which coöperates therewith, one series of shoulders being adapted for use on the "Out" trip of the car and the other series for the "In" trip of the car, said plate being removably attached to a support movable with the time printing member so that it may be reversed in position.

17. In a transfer printing machine, a casing containing movable printing members for printing line and time designations, a line selecting mechanism controlling the movement of the line printing member, a stop mechanism for controlling the movement of the time printing member, said stop mechanism including a plate having two series of stop shoulders, and movable means actuated by the line selecting mechanism and adapted to engage with said shoulders, one series of shoulders being adapted for use on the "Out" trip of the car employing the transfer printing machine, and the other series being adapted for use on the "In" trip, a support for said plate movable with the time printing member, said plate being removably attached to said support on the exterior of the casing whereby at the end of a trip the plate may be removed and reversed in position.

18. In a transfer printing machine, movable printing members for printing line and time designations, a line selecting mechanism including a series of keys one for each

line to which transfer is to be made, a stop mechanism for the time printing member controlled by said line selecting mechanism and including a movable stop device and a member which coöperates therewith, and means for transmitting movement from said line selecting mechanism to said movable stop device comprising a member adapted to be engaged by said keys and to be shifted 10 by said keys different amounts.

19. In a transfer printing machine, movable line and time printing members for printing line and time designations, a line selecting mechanism comprising a plurality of keys one for each line to which transfer is adapted to be made, a stop mechanism for the time printing member controlled by the line selecting mechanism, said stop mechanism including a movable stop device, and 15 a member which coöperates therewith, and means for transmitting movement from said line selecting mechanism to said stop device comprising a notched or stepped plate adapted to be engaged by keys of said line 20 selecting mechanism and to be moved different amounts thereby.

20. In a transfer printing machine, a casting containing rotary line and time printing wheels, gearing for rotating the same, 30 a line selecting mechanism which when actuated interposes a stop in the path of a gear connected to the line printing wheel and limits the movement thereof, a stop mechanism for the time printing wheel controlled by the line selecting mechanism and 35 comprising a movable stop device, and a plate having shoulders which coöperate therewith, said plate being supported on a gear connected with said time printing 40 member.

21. In a transfer printing machine, a casting containing rotary line and time printing wheels, gearing for rotating the same, a line selecting mechanism which when actuated interposes a stop in the path of a gear connected to the line printing wheel and limits the movement thereof, a stop mechanism for the time printing wheel comprising a movable stop device adapted to be 45 actuated by the line selecting mechanism and a plate which coöperates with said stop device, said plate having two series of shoulders, one series coöoperating with said stop device on the "out" trip of the car, and the other on the "in" trip, and said plate being 50 removably supported on a gear connected to the time printing wheel so that it may be readily removed and reversed in position at the end of a trip.

22. In a transfer printing machine, rotary line and time printing wheels, gears connected thereto and adapted to rotate the same different amounts, a line selecting mechanism including a plurality of movable members adapted to positively stop at dif-

ferent positions a gear connected to the line printing wheel, a stop mechanism for the time printing wheel adapted to stop the latter at different positions, said stop mechanism being controlled by the line selecting mechanism and comprising a plate provided with a series of shoulders and removably supported on a gear connected to the time printing wheel, and a stop device which coöperates with said shoulders and is shifted 75 different amounts by said line selecting mechanism.

23. In a transfer printing machine, rotary line and time printing wheels, gears connected thereto and adapted to rotate the same different amounts, a line selecting mechanism including a plurality of movable members adapted to positively stop at different points a gear connected to the line printing member, a stop mechanism for the time printing wheels adapted to stop the latter at different positions, said stop mechanism being controlled by the line selecting mechanism and comprising a plate provided with a series of shoulders and removably supported on a gear connected to the time printing wheels, and a stop device which coöperates with said shoulders and is shifted different amounts by said line selecting mechanism, and means for turning said printing wheels to the limits determined by the line selecting mechanism and by the stop mechanism for the time wheel comprising a shaft and yielding connections between said shaft and the gears connected to the line and time printing wheels respectively.

24. In a transfer printing machine, line and time printing members, means for simultaneously and independently shifting both printing members predetermined amounts from normal position so that when a transfer is printed for any particular line, the time that is printed bears a predetermined relation to the time that the car is scheduled to arrive at the transfer point, and means whereby the normal position of the time printing member may be adjusted.

25. In a transfer printing machine, independently movable line and time printing members, a selecting mechanism which, when actuated to print a transfer for any particular line, interposes stop limits for the printing members, and means for shifting the printing members to the positions determined by the selecting mechanism.

26. In a transfer printing machine, relatively movable line and time printing members, stop devices for permitting variable movements to both printing members so that line and time data can be printed for any transfer line, and means for shifting the printing members from normal position to printing positions determined by the stop devices and for returning the printing mem- 125 130

bers to normal position after the printing operation.

27. In a transfer printing machine, a movable time printing member, and means for controlling the movement of the time printing member comprising a member having definite stop points thereon and a positive movement limiting device coöperating therewith, the relative spacing of said stop points having a fixed relation to the distances between transfer points or stations along the line on which the machine is employed.

28. In a transfer printing machine, a movable time printing member for printing time data for a number of transfer lines, and means for controlling the movement of the time printing member comprising a member having stop shoulders thereon and a positive movement limiting device coöperating therewith, the relative spacing of said shoulders being proportionate to the relative schedule time periods between transfer points.

29. In a transfer printing machine, line and time printing members independently and relatively movable during the operation of the machine for printing line and time data for a number of transfer lines, and means comprising a selecting mechanism for controlling the movements of the line and time printing members so as to cause the time which is printed on a transfer for any particular line to be a predetermined amount later than the time that the car is scheduled to arrive at the transfer point.

30. In a transfer printing machine, line and time printing members, means for simultaneously and independently shifting both printing members predetermined amounts from normal position so that when a transfer is printed for any particular line, the time that is printed bears a predetermined relation to the time that the car is scheduled to arrive at the transfer point, operable means for limiting the movements of the printing members when the latter are shifted, and means whereby the normal position of the time printing member may be adjusted.

31. In a transfer printing machine, a movable time printing member, and means for controlling the movement of the time printing member comprising a stop member having definite stop points thereon, the relative spacing of said stop points having a fixed relation to the distances between transfer points or stations along the line on which the machine is employed and a movable stop device coöperating with said stop member and adapted to be controlled by the operator.

32. In a transfer printing machine, a movable time printing member for printing time data for a number of transfer lines, and means for controlling the movement of the time printing member comprising a member having stop shoulders thereon and a movable stop device coöperating with said stop mem-

ber and adapted to be controlled by the operator, the relative spacing of said shoulders being proportionate to the relative schedule time periods between transfer points.

33. In a transfer printing machine, a die carrier having substantially uniformly spaced dies adapted to print different station designations; a second die carrier having dies adapted to print different time designations; means for bringing corresponding time and station dies to the printing point including a stop member operatively connected with the time die carrier to move simultaneously therewith and having stops spaced proportionally to the running time of a vehicle between stations designated by the station dies; and means for taking impressions from the time and station dies simultaneously presented at the printing point.

34. In a transfer printing machine, a die carrier having substantially uniformly spaced dies adapted to print different station designations; a second die carrier having dies adapted to print different time designations; means for bringing corresponding time and station dies to the printing point including a stop member operatively connected with the time die carrier to move simultaneously therewith and having stops spaced proportionally to the running time of a vehicle between stations designated by the station dies; means for initially adjusting the relative positions of the time die carrier and the stop member; and means for taking impressions from the time and station dies simultaneously presented at the printing point.

35. In a machine for printing transfers, the combination of a die carrier having dies adapted to print time designations; means for positioning different time dies at the printing point including a stop member operatively connected with the die carrier to move simultaneously therewith and having stops spaced proportionally to the running time of a vehicle between stations at which transfers are to be issued, a positive movement limiting device coöperating with said stop member; and means for taking impressions from the die presented at the printing point.

36. In a machine for printing transfers, the combination of a die carrier having dies adapted to print time designations; means for positioning different time dies at the printing point including a stop member operatively connected with the die carrier to move simultaneously therewith and having stops spaced proportionally to the running time of a vehicle between stations at which transfers are to be issued, a positive movement limiting device coöperating with said stop member; means for initially adjusting the relative positions of the die carrier and

the stop member; and means for taking impressions from the die presented at the printing point.

37. In a machine for printing transfers, 5 the combination of a die carrier having dies adapted to print time designations; means for positioning different time dies at the printing point including a stop member operatively connected with the die carrier to 10 move simultaneously therewith and having two series of stops, the stops of each series being spaced proportionally to the running time of a vehicle between stations at which transfers are to be issued, and the stops of 15 one series being arranged in reverse order to those of the other, a positive movement limiting device coöperating with said stop member; and means for taking impressions from the die presented at the printing point.
38. In a machine for printing transfers, 20 the combination of a die carrier having dies adapted to print time designations; means for positioning different time dies at the printing point including a stop member operatively connected with the die carrier to 25 move simultaneously therewith and having two series of stops, the stops of each series being spaced proportionally to the running time of a vehicle between stations at which 30 transfers are to be issued, and the stops of one series being arranged in reverse order to those of the other, a positive movement limiting device coöperating with said stop member; means for initially adjusting the 35 relative positions of the stop member and the die carrier; and means for taking impressions from the die presented at the printing point.

39. In a printing machine a pair of independently movable printing members, a keyboard selecting mechanism and means by which the actuation of a single key controls the movements of both printing members.

40. In a transfer printing machine, for a 45 number of transfer lines, a time printing member for printing a time having a predetermined relation to the time that a car is scheduled to arrive at a transfer point, and means comprising a selecting mechanism having operating members corresponding to the different lines for controlling the 50 movements of the time printing member.

41. In a transfer printing machine, a line printing member, a time printing member 55 for printing a time having a predetermined relation to the time that a car is scheduled to arrive at a transfer point, and means comprising a keyboard selecting mechanism for controlling the movements of said printing 60 members.

42. In a transfer printing machine, a line printing member, a time printing member for printing a time having a predetermined relation to the time that a car is scheduled 65 to arrive at a transfer point, means com-

prising a keyboard selecting mechanism for controlling the movements of said printing members, and means for operating said members.

43. In a transfer printing machine, line 70 and time printing members each normally movable independently of the other, for printing line and time data for a number of transfer lines, means for limiting the movements of said printing members so that 75 the latter will print appropriate line and time data for a selected line, and separate means for operating said members.

44. In a transfer printing machine, line 80 and time printing members for printing line and time data for a number of transfer lines, manually operable mechanism for selectively controlling the extents of movement of the printing members, and separate means for shifting said members amounts determined by the selecting mechanism.

45. In a transfer printing machine, line and time printing members independently movable during the operation of the machine, operable means for limiting the 90 movements of the printing members so as to cause the latter to print appropriate line and time data for any selected line, and means for shifting said members comprising an operating part common to both the 95 printing members.

46. In a transfer printing machine, line and time printing members, operable means for limiting the movements of the printing members, and means for shifting said members comprising a part adapted to be moved by the operator, and having a predetermined length of movement regardless of the extent of movements of the printing members.

47. In a transfer machine, line and time 105 printing members for printing line and time data for a number of transfer lines, means for selectively limiting the movements of the printing members from normal position, and operating mechanism for said members 110 including means for restoring the said members to normal position after a printing operation.

48. In a printing machine, a pair of printing members independently movable during 115 the operation of the machine and means comprising a single selecting mechanism for selectively controlling the movements of both printing members.

49. In a printing machine, two printing 120 members normally independently movable, a selecting mechanism for controlling the movement of one of said printing members, and means whereby the operation of said selecting mechanism controls the movement 125 of the other printing member.

50. The combination of a series of station printing elements corresponding to the stations along a route; a series of time printing elements; both said series of elements being 130

independently movable during the operation of the machine, and a control mechanism adapted to select any one of said station printing elements together with a corresponding one of said time printing elements in accordance with the running time of a vehicle over said route.

51. The combination of a series of station printing elements corresponding to the stations along a route; a series of time printing elements; both said series of elements being independently movable during the operation of the machine, a control mechanism adapted to select any one of said station printing ele-

ments together with a corresponding one of 15 said time printing elements in accordance with the running time of a vehicle over said route; and means for effecting an initial adjustment of the above recited parts according to the time said vehicle starts over said 20 route.

In testimony whereof, I hereunto affix my signature in the presence of two witnesses.

ROBERT E. KIMBALL.
